(57) **CLAIM**

We claim the ornamental design for a remote control housing, as shown and described.

DESCRIPTION

FIG. 1 is a top front isometric view of a first embodiment of a remote control housing in accordance with the present design.

FIG. 2 is a front elevation view of the remote control housing of FIG. 8.

FIG. 3 is a rear elevation view of the remote control housing of FIG. 8.

FIG. 4 is a right side elevation view of the remote control housing of FIG. 8.

FIG. 5 is a left side elevation view of the remote control housing of FIG. 8.

FIG. 6 is a top plan view of the remote control housing of FIG. 8.

FIG. 7 is a bottom plan view of the remote control housing of FIG. 8.

FIG. 8 is a top front isometric view of a second embodiment of a remote control housing in accordance with the present design.

FIG. 9 is a front elevation view of the remote control housing of FIG. 8.

FIG. 10 is a rear elevation view of the remote control housing of FIG. 9.

FIG. 11 is a right side elevation view of the remote control housing of FIG. 10.

FIG. 12 is a left side elevation view of the remote control housing of FIG. 11.

FIG. 13 is a top plan view of the remote control housing of FIG. 12; and,

FIG. 14 is a bottom plan view of the remote control housing of FIG. 13.

(Continued)

The broken lines illustrate portions of the remote control housing that form no part of the claimed design.
